US00D586971S

(12) **United States Design Patent**
Rousso et al.

(10) **Patent No.:** **US D586,971 S**
(45) **Date of Patent:** **** Feb. 17, 2009**

(54) **WASTE DISPOSAL DEVICE**

(75) Inventors: **John Rousso**, Trumbull, CT (US); **Steve Mowers**, Fairfield, CT (US); **John Cichello**, Wooster, OH (US); **Rick Corney**, Akron, OH (US); **Michael Jackson**, Wooster, OH (US)

(73) Assignee: **Playtex Products, Inc.**, Westport, CT (US)

(**) Term: **14 Years**

(21) Appl. No.: **29/293,319**

(22) Filed: **Nov. 16, 2007**

(51) **LOC (9) Cl.** **09-09**

(52) **U.S. Cl.** **D34/7**

(58) **Field of Classification Search** **D34/1-11; 220/908-913; D9/446, 522**

See application file for complete search history.

Primary Examiner—Cynthia E Ramirez*(74) Attorney, Agent, or Firm*—Ohlandt, Greeley, Ruggiero & Perle, L.L.P(57) **CLAIM**

The ornamental design for a waste disposal device, as shown and described.

DESCRIPTION

FIG. 1 is a front perspective view of an exemplary embodiment of a waste disposal device according to the present disclosure;

FIG. 2 is a front view of the waste disposal device of FIG. 1;

FIG. 3 is a rear view of the waste disposal device of FIG. 1;

FIG. 4 is a side view of the waste disposal device of FIG. 1, the opposite side being identical thereto; and,

FIG. 5 is a top view of the waste disposal device of FIG. 1.
